UNITED STATES PATENT OFFICE

EMMET S. MILLER, RUSSELL W. STAMBAUGH, AND GEORGE W. MCKOWN, OF MILWAUKEE, WISCONSIN; SAID MILLER AND SAID STAMBAUGH ASSIGNORS TO MILWAUKEE CORRUGATING COMPANY, OF MILWAUKEE, WISCONSIN

BUILDING MATERIAL

Application filed May 8, 1925. Serial No. 28,821.

This invention relates to certain new and useful improvements in building materials and refers more particularly to an appliance especially adapted for use in the construction of concrete buildings, to provide means for securing the usual metal lath in place.

It is a general object of this invention to provide an improved device of the character described which may be very cheaply produced and which will greatly facilitate the construction of concrete buildings.

Another object of this invention resides in the provision of an improved device of the character described having a shield or protecting member which is embedded in the ceilings and walls prior to the pouring of the concrete and which carry means to which the metal lathing may be readily attached.

It is a still further object of this invention to provide a device of the character described which will lend permanency to buildings and which is so designed as to permit the destruction and removal of the ceiling and wall plaster and the laying of new metallic lathing without necessitating any expensive operation.

With the above and other objects in view which will appear as the description proceeds, our invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, we have illustrated several complete examples of the physical embodiment of our invention constructed according to the best modes we have so far devised for the practical application of the principles thereof, and in which:

Figure 1 is a fragmentary perspective view, partly in section and partly in elevation, taken through the ceiling of a concrete

building, the forms being illustrated as in position for pouring of the concrete;

Figure 2 is a view, partly in section and partly in elevation, taken through Figure 1 on the plane of the line 2-2, with the forms removed and the metal lath secured in place;

Figure 3 is a fragmentary perspective view of a slightly modified form of improved lath mounting member;

Figure 4 is a view similar to Figure 3 of another modified form, and

Figure 5 is a view similar to Figure 3 of still another modified form of our invention.

Referring now more particularly to the accompanying drawing in which like numerals also designate like parts throughout the several views, the numeral 5 designates the usual joists or longitudinal support adapted to be secured in place by suitable braces, not shown, to support the metal forms 6 prior to the pouring of the concrete 7 to form the floor to which the ceiling of the floor below is to be attached.

Heretofore divers tedious and expensive methods have been employed to attach the metal lathing 8 to the ceiling joists, all of which have been rather expensive and have required extremely skilled workmen. Our invention contemplates the provision of elongated shields or protecting members 9 which are placed into molds before the concrete is poured and consequently embedded therein, and which carry means to which the lathing may be readily suitably secured by wires or other means 10, see Figure 2.

In Figures 1 to 3, inclusive, our device is approximately triangular or inverted V-shape in cross-section with its base portion 11 provided with a plurality of apertures 12. The base 11 is slotted at intervals, as at 13 to receive a wire or other anchoring member 14 which is wrapped around the shield member 9 with its medial portion thereabout and its ends twisted, as at 15, and directed laterally, as at 16. With the anchoring wires 14 in

place, the members 9 are placed on the joists 5 between the longitudinal flanges 17 of the forms where they are secured by staples or other means 18. The staples 18 prevent the displacement of the members 9 during the pouring of the concrete and the stamping or packing of the same as is customary.

After the concrete has set, the joists 5 and the forms 6 are removed in the usual manner, 10 the ends of the staples 18 being pulled out of the joists 5 and, if they extend from the ceiling sufficiently to interfere with the laying of the laths, they are bent over.

The lathing is then rapidly secured in place 15 by having the tying wire 10 passed through adjacent openings 12 and then about the transverse rib 19 of the lath the ends of the wire 10 being twisted, as at 20, and preferably bent inwardly to lie within rib 19. If desired, the side walls of the member 9 may be 20 provided at intervals with apertures 21 into which a tit or portion of the concrete 7 projects to afford an additional anchoring means and further assure permanency.

25 In Figure 3 one side of the member 9 is preferably extended beyond the other and then folded or bent thereover, as at 22, to cover the seam and thereby protect against the entrance of concrete while being poured, 30 such as would happen in the event the member 9 became slightly bent during handling.

In that form of our invention previously described, the portions of the base 11 between the openings 12 form members to which the 35 lathing is tied by the wires 10, and in Figure 4 the securing member is a distinct element, being preferably in the form of an elongated rod or wire 23 having loops or return bends 24 at intervals which are engaged by the anchor wires 14. The anchor wires pass outwardly through openings in the top of the shield or protecting member 9 and are twisted, as at 25, with their ends directed laterally, as at 26, to insure the proper anchoring of the 40 device. In this form of our invention, the members 9 are of inverted U or trough shape and may be, if desired, provided with lateral longitudinal flanges 27.

That form of our invention illustrated in 50 Figure 5 is somewhat similar to that form previously described with the exception that the anchoring wires 14 form the means to which the tie wires 10 are secured. The member 9 is of inverted V-shape with its base or 55 bottom open and the tie wires pass through openings 28 in the walls thereof near the lower edge, that portion 29 of the anchor wires traversing the open bottom of the V providing means to which the wires 10 may be attached. In this form of our invention, the tie wires 14 are also twisted, as at 15, and have their ends 16 directed laterally. The 60 longitudinal edges of the members 9 may be flanged laterally, as at 27, if desired.

65 From the foregoing description taken in

connection with the accompanying drawing it will be readily obvious to those skilled in the art to which an invention of this character appertains that we provide a novel and improved device for use in construction of concrete buildings, which will permit the convenient laying of metal wall and ceiling lathing at a minimum cost and which will be 70 very durable in nature.

What we claim as our invention is:

1. A device of the character described, comprising a protecting member adapted to be embedded in the concrete of a building at the time of pouring, anchoring means carried by said member and including a laterally projecting part, additional anchoring means in the form of an opening in said member into which a tit of concrete forms, and means formed in said protecting member and to which lathing may be secured by tie wires 80 passed into the interior of the protecting member and over and around said last mentioned means to be tied thereto.

2. A device of the character described, consisting of an inverted V-shaped member adapted to be placed in the form of a building prior to the pouring of the concrete, said member having a plurality of spaced apertures in its base wall to provide intervening webs to which a tie for metal lathing may be 90 secured.

3. A device of the character described, comprising an inverted V-shaped member adapted to be placed in the form of a building prior to the pouring of the concrete, said member having a plurality of spaced apertures in its base wall to provide means to which a tie for metal lathing may be secured, and means for anchoring said member in the concrete, including anchor wires wrapped 100 about said member.

4. A device of the character described, comprising an inverted V-shaped member adapted to be placed in the form of a building prior to the pouring of the concrete, said member having a plurality of spaced apertures in its base wall to provide means to which a tie for metal lathing may be secured, and means for anchoring said member in the concrete and including anchor wires wrapped 110 about said member and apertures in the side walls of said member in which tits of concrete form.

5. A device of the character described comprising an elongated, substantially trough-shaped member, said member being provided with a base portion perforated at a plurality of points, means for anchoring the member in the concrete of a building, and means engageable in spaced perforations of said base portion for securing thereto metal lathing.

6. A device of the character described comprising a substantially triangular-shaped protecting member adapted to be imbedded 120

in the concrete of a building at the time of pouring, said member having a flat base portion perforated at a plurality of points spaced longitudinally thereof, and a tie wire passed through adjacent perforations and extended from the flat base of said member for attachment to a metal lathing.

5 In testimony whereof we affix our signatures.
